UNITED STATES PATENT OFFICE

2,188,926

LOCOMOTIVE JOURNAL OILER

Joseph P. Savage, Columbus, Nebr.

Application February 4, 1938, Serial No. 188,771

14 Claims. (Cl. 308—91)

The present invention relates to journal box lubricators or oilers and more particularly to certain improvements in journal box lubricators such as disclosed in my co-pending application, Serial Number 83,986, filed June 6, 1936, now

5 Patent No. 2,110,243.

The primary object of the present invention is to provide an improved locomotive journal oiler which may be readily substituted for the usual 10 types of cellars, and embodying improved means for delivering the oil in thin streams upon the journal.

A further object resides in the improved construction of the oil feeding means, having an 15 arrangement for oiling said means.

A further object is to provide a driving box 20 cellar which may be readily filled and drained of oil without removal from the journal box, and also embodying means for gauging the amount 25 of oil in the cellar.

A still further object resides in the improved 30 formation of the crown brass for use in connection with the improved driving box cellar to provide force feed lubrication for the journal.

25 Other objects and advantages of the present invention will be apparent from the following detailed description, taken in connection with the accompanying drawings, forming a part of this specification and in which drawings:

30 Figure 1 is a vertical transverse section thru the journal oiler shown applied and looking at the inner end of the driving box.

Figure 2 is a vertical longitudinal section thru 35 the oiler shown applied to the driving box and showing the oil feeder unit in elevation.

Figure 3 is a fragmentary elevation of the lower portion of the oiler, looking at the inner end of the oiler and showing its application to the driving box.

40 Figure 4 is a top plan view of the journal oiler with certain portions broken away.

Figure 5 is an end view of the lubricating means shown removed from the oil container, with portions broken away.

45 Figure 6 is an enlarged detail section on line 6—6 of Figure 4 and not showing the wheel receiving cup.

In the drawings and wherein like reference 50 characters designate corresponding parts throughout the several views, the letter A designates a driving box provided with the improved journal oiler B and crown brass C. The letter D designates a driving axle journal mounted in the box A and upon the outer ends of which the driving wheels 55 are mounted as at E in Figure 2.

The driving box A may be of usual construction having the depending side arms 5 between the upper ends of which the crown brass or bearing C is mounted. This crown brass C has its lower lower edges beveled and resting upon dove-tailed ribs 6 formed longitudinally of the box. Formed longitudinally in the upper concaved side of the brass C is an oil groove 7 which terminates short of the ends of the brass as in Figure 2. A tapped hole 8 extends from one end 5 of the brass to a point above one end of the longitudinal groove 7, and a hole 9 is drilled from the bottom of the groove to meet with the inner-end of the tapped hole 8 whereby oil may be fed to the groove 7 along the upper side of the 10 journal. The brass is also circumferentially grooved adjacent its inner end as at 10, the groove extending from side to side of the brass as shown by dotted lines in Figure 1. With this arrangement of grooving and tapping the crown 15 brass, a force feed lubrication system is provided which may be used in conjunction with the oiler B.

Referring now to the improved journal oiler B, the same is adapted to removably fit between 25 the arms 5 beneath the journal D and be supported upon a flat brace plate 11 for the lower ends of the arms 5. Depending from each corner of the brace plate 11 is an apertured lug 12 and these lugs receive cellar or keeper bolts 13 for 30 removably retaining the plate in place.

Supported upon the plate 12 is an oil container or cellar 14 of box-like formation providing vertical side walls 15, inner and outer end walls 16 and 16' respectively, and a flat bottom wall 35 17. The upper ends of the side walls 15 interfit with the lower undercut sides of the dove-tail ribs 6 and as shown in Figure 1, these side walls are in contact with the inner faces of the arms 5. The upper edges of the end walls 16 and 16' 40 are of semi-circular shape for receiving the journal D, the radius of curvature of the edge being slightly greater than that of the journal.

Telescopically associated respectively with the end walls 16 and 16' are oil retaining units 18 and 45 19 which are of like construction and which are normally spring urged upwardly into engagement with the journal D. Each oil retaining unit embodies an inner guide plate 20 slidably engaging the inner surface of an end wall of the cellar 14 50 with the end edges of the plate slidably engaging the side walls 15 of the cellar. Disposed over the outer face of the end wall is an outer or dust plate 21. These plates 20 and 21 have straight lower edges and at their upper edges are of semi-cir- 55

cular shape for receiving the journal D. Secured between the upper semi-circular edges of the plates 20 and 21 is a felt strip 22 for engagement with the journal, and this strip acts as a spacer 5 for the plates so that the end wall of the cellar may extend between the plates. Secured to the inner side of the guide plate 20 is a wooden block 23 having a semi-circular shaped upper face conforming to the journal. A series of rivets or the like 24 serve to secure the elements 20, 21, 22 and 23 together as a unit along the upper arcuate edges of the elements.

Mounted longitudinally beneath each block 23 is a support 25 upon which the lower ends of coil springs 26 seat. The upper ends of these springs 26 extend into pockets in the lower edges of the blocks 23, whereby the springs act to normally urge the oil retaining units upwardly into contact with the journal.

Slidably fitting into the cellar 14 to rest upon the bottom wall 17 thereof is a lubricating unit embodying an open rectangular shaped frame formed with shallow end walls 27 fitting between the supports 25, and higher side walls 28 providing 25 wiper plates which are normally spring urged toward one another at their upper portions as shown in Figure 5. Secured along the upper edges and at the inner side of each wiper plate 28 is a felt wiper strip 29 for wiping contact with 30 the journal along lines even with the upper ends of the units 18 and 19.

Mounted within the frame of the lubricating unit is an oil feeder 30 for delivering oil in the cellar 14 to the journal. This oil feeder 30 comprises a mounting plate 31 secured to the lower portion of one of the side walls 28 and formed at its upper edge with spaced apart hinge eyes 32 receiving the ends of a horizontal hinge pin 33. Hinged at one edge upon the pin 33 between the 40 eyes 32 is a hinge plate 34 having spaced arms 35 provided at their free ends with eyes 36 parallel with the hinge eyes 32. Supported at one end between the arms 35 is a semi-circular shaped cup 37.

Fitting at its ends in the eyes 36 is a shaft 38, and rotatable on this shaft between the eyes 36 is an oiling unit embodying a sleeve or hub member 39 provided midway of its ends with a wheel 40 which is rotatable in the cup 37, and is adapted 50 to have rolling contact with the journal. Provided on the sleeve 39 at each side of the wheel 40 are flat blade-like propellers 41 which taper to a point at their outer ends. These propellers rotate in the space between the sides of the cup 37 and the arms 35 and are of a length slightly less than the diameter of the wheel 40 so as to not contact the journal. These propellers dip into the oil in the cellar 14 and throw the oil in two thin streams upon the journal.

The wheel 40 is held in contact with the journal by coil springs 42 acting between brackets 43 bent out from the mounting plate 31, and the under side of the plate 34.

Mounted upon the upper side of the hinge plate 65 34 is a drip catch pan 44 which may have a screen over its upper side and this pan is intended to catch excess oil scraped from the journal for lubricating the oiling unit. Connected at one end with one end of the pan 44 is an oil delivery 70 tube 45 having its opposite end communicating with an axial oil duct 46 opening at one end of the shaft 38. The inner end of this duct 46 opens radially of the shaft midway between the ends of the sleeve 39. The shaft 38 is held stationary 75 in the eyes 36. Because of the high speed of ro-

tation of the wheel 40 and propellers 41, the oil is thrown by centrifugal action away from the bearing 39 so that this bearing is not properly lubricated. The delivery tube 45 will insure proper lubrication of the bearing 39 and allow for a lower 5 oil level being maintained in the cellar 14. No oil is contained in the cup 37 and any excess oil delivered to the bearing shaft 38 works to the ends of the sleeve 39 and returns to the oil cellar.

Pivotedly mounted in the open frame of the lubricating unit is a pair of U-shaped scrapers each embodying a scraper bar 48 extending parallel to the journal, and arms 49 pivoted at their lower ends as at 50 to the inside of the frame end walls 27. Connecting the lower portions of the arms 49 of the scrapers are coil springs 51 which serve to retain the scraper bars in contact with the journal below the felt strips 29. One end of each of the scraper bars 48 is loosely pivoted upon the arm to permit the bars 20 to move into contact thruout their length with the journal.

Provided at the inner end of the cellar 14 is a three way elbow 52 providing a combination filler, gauge and drain for the cellar. The upstanding branch of the elbow which provides the filler opening, is provided with a float gauge 53. A plug 54 is provided in the horizontal branch of the elbow for draining the oil cellar.

The journal oiler B is removably retained in place by means of a single pin or bolt 55 projecting from the lower portion of one of the arms 5 and over which a washer 56 is placed and retained by a cotter pin. As shown in Figure 3, the washer projects over the face of the inner cellar wall 16. 35

As shown in Figures 1 and 4, the blocks 23 are rabbetted at their inner sides along each vertical edge of the block and across the bottom of the block to provide clearance for inward swinging of the scraper arms 49, and space for the coil 40 springs 51 connecting the scrapers. The rabbets at the vertical edges of the blocks 23 also permit inward swinging of the wiper plates 28 which, as shown in Figure 4, have their end edges extending to the blocks 23.

Secured to the dust plate 21 of the outer oil retaining unit 18 is a hub plate 60 to which is secured a felt wiper pad 61 for contact with the hub of the wheel E.

Changes in details may be made to the shape, size, and arrangement of parts, without departing from the spirit of the invention or the scope of the following claims.

I claim:

1. In a journal box lubricator, an oil cellar, 55 a lubricating unit fitting in the cellar embodying a pair of yieldable wiper plates inherently spring-urged toward the journal, an oil feeder hinged upon one of said plates embodying an impelling wheel and a pair of spaced apart propellers rotatable with the wheel for throwing oil upon the journal, and spring means normally urging the feeder toward the journal.

2. In a journal box lubricator, an oil cellar, 65 an open frame member resting upon the bottom of the cellar embodying side walls providing wiper plates inherently spring-urged at their upper ends against the journal, an oil retaining unit at each end of the cellar, spring means normally urging the units toward the journal, 70 and an oiling unit hinged upon one of said wiper plates and normally spring-urged against the journal.

3. In a journal box lubricator, an oil cellar, 75 an open frame member resting upon the bottom

of the cellar embodying side walls providing wiper plates inherently spring-urged at their upper ends against the journal, an oil retaining unit at each end of the cellar, spring means 5 normally urging the units toward the journal, scrapers pivoted inwardly of each wiper plate, spring means normally urging the scrapers against the journal, and an oiling unit hinged upon one of the wiper plates embodying an impelling wheel and a pair of spaced apart propellers rotatable with the wheel, and spring means normally urging the wheel against the journal.

4. In a journal box lubricator, an oil cellar, 10 an open frame fitting in the cellar embodying end plates and side walls providing wiper plates, scrapers pivoted on said end plates, spring means normally urging the scrapers toward one another, an oil retaining unit telescopically associated with each end of the cellar, spring means normally urging the oil retaining units upwardly, a hinge plate hinged to one of said wiper plates, a wheel journaled on the hinge plate, flat propellers rotatable with the wheel, and spring 15 means normally urging the hinge plate upwardly and the wheel into rolling contact with the journal.

5. In a journal box lubricator, an oil cellar embodying end and side walls, an open frame 20 fitting in the cellar embodying end and side plates, said side plates forming journal wiper plates, an oil retaining unit telescopically associated with each end wall of the cellar, spring means normally urging the oil retaining units 25 upwardly, an impelling wheel supported from one of the wiper plates, oiling blades rotatable with the wheel, and spring means normally urging the wheel against the journal.

6. In a journal box lubricator, an oil cellar embodying end and side walls, an oil retaining 30 unit telescopically associated with each end wall of the cellar, spring means normally urging the oil retaining units upwardly, and a lubricating unit fitting in the cellar between the oil retaining 35 units embodying an open frame having side walls providing wiper plates, a supporting plate hinged upon one of the wiper plates, an oiling unit journaled on the supporting plate embodying an impelling wheel and a pair of oiling blades, and 40 spring means normally urging the supporting plate upwardly at its free end.

7. In a journal box lubricator, an oil cellar embodying end and side walls, an oil retaining 45 unit telescopically associated with each end wall of the cellar, spring means normally urging the oil retaining units upwardly, and a lubricating unit fitting in the cellar between the oil retaining 50 units embodying an open frame having side walls providing wiper plates, a supporting plate hinged upon one of the wiper plates, an oiling unit journaled on the supporting plate embodying an impelling wheel and a pair of oiling blades, a 55 drip catch pan on the supporting plate, an oil tube connected with the pan for lubricating the oiling unit, and spring means normally urging the supporting plate upwardly.

8. In a journal box lubricator, an oil cellar embodying end and side walls, an oil retaining 60 unit vertically movable on each end wall, spring 65 means normally urging the units upwardly, an open frame supported in the cellar between the

oil retaining units embodying side walls providing wiper plates having an inherent tendency to spring toward one another, a supporting plate hinged upon one of the wiper plates, an oiling unit journaled upon the free end of the supporting plate embodying a sleeve provided with an impelling wheel midway of its ends and an oiling blade spaced at each side of the wheel, a drip catch pan supported on the supporting plate, an oil tube connecting the pan and oiling 10 unit for lubricating said sleeve, and a hinged scraper inwardly of each wiper plate.

9. In a journal box lubricator, an oil cellar, an open frame supported in the cellar, a lubricating unit hingedly supported on the frame embodying 15 an impelling wheel and a pair of oiling blades rotatable with the wheel, spring means normally urging the unit upwardly in the cellar, a scraper pivoted on the frame for yieldably engaging the journal, and drip catching and feeding means 20 for lubricating the impelling wheel.

10. In a journal box lubricator, an oil cellar, an open frame supported in the cellar embodying end and side plates, a scraper pivoted on the end plates, an oil feeder unit embodying a supporting plate hinged upon one side plate of the frame, a shaft mounted at its ends in the supporting plate, a cup carried by the supporting plate, an oiling unit journaled on said shaft embodying an impelling wheel rotatable in the cup 30 and a pair of oiling blades rotatable with the wheel, drip collector means for catching oil from the scraper, and means for conveying oil from the drip collector means to said shaft for lubricating the oiling unit.

11. In a journal box lubricator, an oil cellar, an open frame mounted in the cellar embodying side walls providing wiper plates, a scraper embodying arms pivoted on the frame and a scraper bar connected to the upper ends of the arms with 40 one end of the scraper bar having a pivoted connection with its arm, and a lubricating unit carried by the frame embodying spaced apart oiling blades and means for rotating the blades from the journal.

12. In a journal box lubricator, an oil cellar embodying end and side walls, an oil retaining unit telescopically associated with each end wall and each embodying a dust plate, a hub plate provided with a hub wiper secured to one of said dust plates, and a lubricating unit fitting in the cellar between the oil retaining units embodying means for delivering oil to the journal upon rotation of the journal.

13. In a journal box lubricator, an oil cellar, an open frame supported in the cellar, and an oil feeder unit hinged upon the frame embodying a cup, an impelling wheel rotatable in the cup, oiling blades rotatable with the wheel for delivering oil to the journal, and drip collector 55 means for lubricating said wheel.

14. In a journal box lubricator, a lubricating unit embodying an open frame, a plate hinged along one edge to the frame, an oiling unit journaled in the free end of the plate embodying an impelling wheel and a pair of tapering oil feeding propellers, a drip catch pan on said plate, and an oil tube for conveying oil from the drip catch pan to the bearing for the impelling wheel.
